UNITED STATES PATENT OFFICE.

HARRY E. REED, OF SALEM, MASSACHUSETTS.

GAME APPARATUS.

No. 852,904.

Specification of Letters Patent.

Patented May 7, 1907.

Application filed October 9, 1906, Serial No. 338,134.

To all whom it may concern:

Be it known that I, HARRY E. REED, of Salem, in the county of Essex and State of Massachusetts, have invented certain new and useful Improvements in Game Apparatus, of which the following is a specification.

This invention relates to the type of game apparatus in which an inclined board is employed and loose balls adapted to roll down the incline of the board, the pockets being adapted to arrest such balls as happen to coincide with the pockets in their course down the board.

15 The invention has for its object to provide a game apparatus of this character with means whereby the entrance of a ball into any pocket of the board will operate a signal which corresponds to the pocket, and adds to 20 the attractiveness of the game.

The invention consists in the improvements which I will now proceed to describe and claim.

Of the accompanying drawings, forming a 25 part of this specification—Figure 1 represents a side elevation of a game apparatus embodying my invention. Fig. 2 represents a front elevation of the signal board or frame shown in Fig. 1. Fig. 3 represents a top plan 30 view of the game board shown in Fig. 1. Fig. 4 is a section illustrating the contacts at the lower end of the board. Fig. 5 represents a section on line 5—5 of Fig. 3. Figs. 6 and 7 represent diagrams of the electrical 35 connection.

The same letters of reference indicate the same parts in all the figures.

In the drawings 12 represents a board, which when in use is supported in an inclined 40 position by any suitable means, such as those shown in Fig. 1. The board is provided with suitable pockets adapted to engage and retain balls rolling loosely down the board. I have shown two series of pockets, the pockets of 45 one series being circular openings 13 formed in the board, and having inclined or tapered sides 13'. The pockets of the other series are recesses or stalls 14, having converging sides 14' preferably formed by attaching a 50 serrated block or strip 15 to the lower portion of the board. The board may also be provided with pins 16, projecting upwardly from the upper surface of the board, and adapted to deflect balls rolling down the 55 board, and cause the balls to take a zigzag course.

17 represents a cover constructed as a signal board and which is preferably connected by hinges 18 with the upper end of the game board 12, and is provided with a series of 60 signals corresponding in number with the pockets in the game board, said signals being preferably incandescent lamps 19. Said cover 17 is supported in its vertical position by any suitable means, such for instance as 65 the brace 17'. Each signal is included in a normally open electric circuit, which includes terminals located in such relation to the ball-engaging pockets that when a ball of a conducting material, such as iron or steel, enters 70 one of said pockets, it will close an electric circuit, and thus operate the corresponding signal. In Fig. 6 I show a diagram of the connections between some of the lamps 19 and circuit terminals 20 located in the pockets 14. In Fig. 7 I show a diagram of the connections between other lamps 19 and circuit terminals 21 located in the pockets 13. In each case the arrangement is such that when a circuit-closing ball enters either of 80 the pockets, a circuit is closed through the corresponding lamp 19, which is illuminated, and thus calls attention to the success which has attended the efforts of the player sending the ball. The removal of the ball from the 85 pocket, breaks the circuit, and the lamp is extinguished.

The portions of the circuit wires which pass from the game board 12 to the signal board 17, are grouped together in flexible 90 cables 22, which are adapted to conform to the position of the signal board so that the latter may be closed down upon the game board when the apparatus is not in use without effecting the electrical connections. 95 Hooks 23 may be affixed to the signal board adjacent to the lamps 19, said hooks being used to support prizes which are awarded to the successful players.

The balls may be projected by the player 100 through the instrumentality of a spring-pressed plunger or piston 24, movable in a narrow way or passage 25, near one edge of the game board, the piston being retracted by means of a handle 26 connected with it, and then released allowing the spring to project the piston, and with it a ball placed in the passage 25 in front of the piston. The board is provided with a curved deflecting wall 27, which turns the projected ball backwardly to 105 toward the lower end of the board.

While I have specified an electric signal, I

do not desire to be understood as limiting myself thereto, although a signal operated by the closing of an electric circuit when a ball enters a pocket, is superior to any other type 5 of signal of which I am aware. It is obvious that a mechanical signal operated by the weight or impact of the ball as it enters a pocket, may be employed without departing from the spirit of my invention.

10 I claim:

1. A game apparatus comprising a game board provided with pockets, a cover hinged to said board and provided with signals corresponding to said pockets, contacts in said 15 pockets, and conductors extending from said contacts to said signals.

2. A game apparatus comprising a game board provided with pockets, a cover hinged to said board and provided with signals corresponding to said pockets, spaced apart contacts located in said pockets, conductors extending from said contacts to said signals, and circuit closing balls of conducting material adapted to enter said pockets and bridge 25 said contacts.

3. A game apparatus comprising a game board provided with pockets having tapered sides, spaced apart contacts engaging the sides

of said pockets, a cover hinged to said board and provided with signals corresponding to 30 said pockets, conductors extending from said contacts to said signals, and circuit closing balls of conducting material adapted to enter said pockets and bridge said contacts.

4. A game apparatus comprising a game 35 board provided with pockets, a cover hinged thereto and provided with signals corresponding to said pockets, contacts in said pockets, conductors extending from said contacts to said signals, and means for supporting said 40 cover in an approximately vertical position.

5. A game apparatus comprising a game board provided with pockets, spaced apart contacts accompanying said pockets, signals corresponding to said pockets, conductors 45 extending from said signals to said contacts, and circuit closing balls of conducting material adapted to enter said pockets and bridge said contacts, each ball, when in a pocket, forming part of the circuit.

50 In testimony whereof I have affixed my signature, in presence of two witnesses.

HARRY E. REED.
